Letters Patent No. 2381. Dated Aug. 14. 1866.

Design for Coffin Trimminings

The design is referred to in the Letters Patent and making part of the same.

To all whom it may concern:

Be it known that S. D. Arnold of New Britain Hartford County and State of Connecticut have invented a new and Improved Design for Coffin Trimminings; and I do hereby declare that the following is a full, clear and exact description thereof, which will enable others skilled in the art to make and use the same, reference being had to the accompanying drawing forming part of this specification.

The present invention relates to a new and Improved Design for trimminings to coffins, burial cases or caskets and other similar receptacles used for the burying of the dead which design is illustrated in the accompanying plate of which the

Figure is a photographic view of the same. This Design consists of an ornamental oval shaped wreath A, which is at suitable points about, and around it is ornamented with roses B, rose buds C, and leaves D, interspersed or interposed between the same; the series of roses, rose buds, and leaves being joined and intertwined by the Vines E, that at the top and bottom of the wreath cross each other, and are relieved by leaves and buds, as plainly shown in the accompanying plate.

I claim as new and desire to secure by Letters Patent, the Design herein described and shown in the accompanying plate of illustration.
